UNITED STATES PATENT OFFICE.

JOHN PLATT, WILLIAM PLATT, AND HENRY PLATT, OF HARROW, ENGLAND.

CARDING ENGINE OR MACHINE.

Application filed September 12, 1927, Serial No. 218,887, and in Great Britain April 4, 1927.

This invention relates to carding engines and is more especially concerned with the cylinder or swift and the flats or "workers" of carding engines and with the clothing for the same.

According to the present invention the cylinder or swift is provided with a clothing or carding surface comprising straight, rigid and pointed teeth on a metal wire or strip-like foundation and is used in conjunction with flats (or workers or similar rollers) provided with a clothing or carding surface having flexible or resilient teeth such as are provided in the ordinary card clothing comprising a leather or fabric foundation with wires or staples inset therein in such manner and of such character as to be flexible or resilient and capable of yielding when meeting with resistance as in the carding operation. The said straight, rigid and pointed teeth of the clothing or carding surface on the cylinder or swift serve to hold the material securely whilst it is lightly or gently engaged by the resilient teeth on the flats or workers which produce a kind of light brushing action on the material as hereinafter more fully described.

In order that the invention may be clearly understood and readily carried into effect, the same will now be more fully described with reference to the accompanying diagrammatic drawings, in which:—

Figure 1 illustrates a construction of cotton carding engine with the cylinder or swift and the flats arranged in the usual manner but provided with the different types of clothing or carding surfaces according to the present invention.

Figure 2 is an enlarged view showing one of the flats and part of the cylinder or swift with the different carding surfaces.

Figure 3 illustrates a "worker" or similar roller provided with the clothing having flexible or resilient teeth in conjunction with part of the cylinder or swift provided with the clothing having straight, rigid and pointed teeth.

Figure 4 illustrates a side view on an enlarged scale of the straight, rigid and pointed teeth on the wire like foundation in conjunction with the clothing comprising the flexible teeth as provided on the flat or worker.

Figure 5 is a sectional view taken along part of the cylinder or swift and showing more particularly the arrangement thereon

of the straight, rigid or pointed teeth on the wire-like foundation.

In the said drawings, A represents the cylinder or swift. BB indicate a series of 60 carding flats arranged to travel in the usual manner in relation to the cylinder or swift. C represents a worker or similar roller such as is used in a wool carding engine arranged in the usual manner in relation to the cylinder or swift A. The clothing for the cylinder or swift A in both the examples illustrated comprises the wire or strip-like foundation D¹ on which the straight, rigid and pointed teeth D are formed or provided. The 70 said wire-like formation D¹ with the teeth D is adapted to be wound or placed around the cylinder or swift in any appropriate manner to provide the carding surface of which the teeth are quite rigid or non-resilient and are 75 inclined at any suitable angle for carding. The wire-like foundation D¹ may be wider than the teeth so as to provide lateral projections which serve as distance pieces to separate the circumferential rows or convolutions 80 of the teeth as shown in Figure 5. The carding surface or clothing for the flats B as shown in Figures 1 and 2 and for the workers C as shown in Figure 3 may be of the usual type comprising a flexible foundation of rubber E¹ and fabric E² and flexible or resilient teeth E which are shown more particularly in Figure 4 may be bent or knee shaped. Referring more particularly to the example shown in Figure 1, the cylinder or swift A 90 and the flats B having the different clothings as shown more particularly in Figures 2 and 4 are mounted to operate as is usual in cotton carding engines and this combination of rigid teeth D on the cylinder or swift A and 95 the flexible or resilient teeth E on the flats B enables improved carding to be effected compared with that produced when both the cylinder or swift and the flats are clothed with the usual form of card clothing having 100 the flexible or resilient teeth. The rigid teeth D on the cylinder or swift grip or hold the textile fabrics more satisfactorily than do the flexible or resilient teeth when such are used on the cylinder or swift whilst the 105 flexible or resilient teeth E on the flats B effect an efficient but light brushing action for combing or straightening out the fibres whilst the latter are firmly held by the rigid teeth D on the cylinder or swift. The flexible or resilient teeth E of the clothing on the flats take up as a brush would the impurities,

seeds, neps, etc., which become embedded in the flat stripping as is well known, and the said teeth also tend to allow the impurities to pass through the card without damage to the 5 rigid toothed clothing on the cylinder or swift. The operation performed by the cylinder or swift and the flats clothed in the manner described is similar to the old hand carding process wherein the fibres were held 10 firmly in one hand and the loose ends brushed or combed with a flexible piece of card or comb. The effect produced by the combination of the different clothings on the cylinder and flats according to this invention cannot 15 be obtained in a carding engine where the cylinder or swift is covered with the clothing having flexible or resilient teeth and is used in conjunction with flats having flexible or resilient teeth for the reason that the fibres 20 are not securely held by the flexible or resilient teeth on the cylinder or swift so that they are constantly slipping from the flexible or resilient teeth of the cylinder to the flexible or resilient teeth on the flats or vice 25 versa and therefore as the fibres are not firmly held by the flexible teeth on the cylinder they cannot be effectively straightened out. In the present invention however, the 30 rigid teeth on the cylinder enable the fibres to be held under all conditions of working so that the flexible teeth on the flats can effectively straighten out the firmly held fibres and in so doing they can bend or yield to effect the soft brushing action as hereinbefore referred to. Thus better carding is 35 effected with the additional advantage that there is less waste produced than is the case when both the cylinder or swift and the flats are provided with the resilient or toothed clothing wherein slipping of the 40 fibres from the teeth of the cylinder to the teeth of the flats and vice versa is responsible for much waste. We may provide in con-

junction with the improved combination according to this invention a doffer F which 45 may be clothed with straight, rigid and pointed teeth to assist in automatically stripping the cylinder during working, but the doffer may be clothed or covered with the ordinary flexible or resilient teeth. Although 50 the invention is especially applicable to the carding of cotton, where carding flats are used, it can of course be used in connection with the carding of wool or other materials in which rollers or workers are used instead 55 of flats and in this case the workers are clothed with the clothing having the flexible or resilient teeth E on the foundation E¹, E² see Figures 3 and 4 for co-operating with the rigid or non-resilient teeth D of the clothing 60 on the cylinder or swift. The advantages above referred to in describing the invention in relation to the combination of the flats and cylinder clothed as aforesaid for cotton carding are obtainable in a wool carding machine 65 wherein the workers are provided with the resilient teeth for co-operating with the rigid teeth on the clothing of the cylinder or swift.

What we claim and desire to secure by 70 Letters Patent of the United States is:—

1. In a carding machine, the combination with flats or workers provided with a clothing comprising resilient teeth, of a swift 75 clothed with a clothing having straight, rigid and pointed teeth.

2. In a carding machine, the combination with flats or workers provided with a clothing comprising resilient teeth, of a swift 80 clothed with a clothing in a form of a wire which is wound around the swift and is provided with straight, rigid and pointed teeth.
